**HORMONE PELLET IMPLANTER FOR ANIMALS
OR SIMILAR ARTICLE**

Nat Cordis, Crown Farm, Silver Lake, Wis.

Filed Apr. 18, 1960, Ser. No. 60,232

Term of patent 14 years

(Cl. D83—12)

Fig. 1 is a right side elevational view of a hormone pellet implanter for animals or similar article embodying my new design, the left side not shown being substantially like the right side shown;

Fig. 2 is a top plan view thereof;

Fig. 3 is a front elevational view thereof; and

Fig. 4 is a rear elevational view thereof.

I claim:

The ornamental design for a hormone pellet implanter for animals or similar article, as shown and described.
